FREDERICK SNOW, OF CHICAGO, ILLINOIS, ASSIGNOR, BY MESNE ASSIGNMENTS, TO CONKLING COMPANY, OF CHICAGO, ILLINOIS, A CORPORATION OF ILLINOIS.

DRIVING AND REVERSING MECHANISM.

No. 841,061.

Specification of Letters Patent.

Patented Jan. 8, 1907.

Application filed September 8, 1902. Serial No. 122,532.

To all whom it may concern:

Be it known that I, FREDERICK SNOW, a resident of Chicago, Cook county, Illinois, have invented certain new and useful Improvements in Driving and Reversing Mechanism, of which the following is a specification.

My invention relates to driving and reversing mechanism, and is especially applicable to the operation of washing-machines such as are used in laundries, hotels, hospitals, &c. It is necessary to check and reverse the motion of machines of this character in order to enable them to properly perform their functions, as will be hereinafter fully set forth, and for the purposes of illustration I will describe my invention as applied to one of these devices.

These are rotary devices and are characterized by a large cylindrical shell containing a rotary cylinder wherein the articles or garments to be washed are placed. The shell is partially filled with water and the cylinder, which has perforated walls, is rotated first in one direction and then in the other to agitate and wash the articles within it.

A power mechanism is provided for rotating the washer-cylinder, and this mechanism is intended to operate the cylinder in the two directions and of necessity includes a reversing mechanism.

The driving and reversing mechanism most in use comprises a driving-shaft having fixed and loose pulleys for belts, which operate in different directions and for which an automatic belt-shifter is provided. This driving mechanism is objectionable by reason of the fact that the belt-shifter does not operate with accuracy as to time; also, the belts are apt to slip, with the result that the cylinder is rotated farther in one direction than in the other, the frequent recurrence of which causes the clothing or articles in the cylinder to form into rolls or wads, which prevents their thorough cleansing. Furthermore, the washers that are now in use are noisy and lack durability.

The primary object of this invention is to provide a rotary washer which will not roll, wad, or ball up the articles during the washing thereof.

The particular object of the invention is to improve the construction and operation of

the driving and reversing mechanism for washers to the end that the same shall be rendered positive and accurate in operation, shall be readily adjustable, noiseless in operation, durable, neat in appearance, shall require little expert attention, and shall occupy less space than similar devices now in general use.

My invention consists generally in a washer shell and cylinder, the latter having a driving gear or member in combination with a driving-shaft engaged with said member, a driving pulley or member provided upon said shaft, means in connection therewith for driving said shaft in either direction, and an automatic reversing device associated therewith; and, further, my invention consists in particular constructions and in combination of parts, all as hereinafter described, and particularly pointed out in the claims.

My invention will be more readily understood by reference to the accompanying drawings, forming a part of this specification, and in which—

Figure 1 is a plan view of a washing-machine embodying my invention. Fig. 2 is an end view thereof. Fig. 3 is a vertical longitudinal section on the line 3^A 3^A of Fig. 1. Fig. 4 is an enlarged vertical longitudinal section of the driving and reversing mechanism on the irregular line 4^B 4^B of Fig. 2. Fig. 5 is an enlarged vertical section on the line 5^C 5^C of Fig. 4. Fig. 6 is a similar view on the line 6^D 6^D of Fig. 4. Fig. 7 is a horizontal sectional detail on the line 7^E 7^E of Fig. 2. Fig. 8 is a detail section on the line 8^F 8^F of Fig. 4. Fig. 9 is a similar section on the line 9^G 9^G of Fig. 4. Fig. 10 is a perspective view of the reversing-clutch, and Fig. 11 is a similar view from the opposite end of the clutch.

As shown, 2 represents the shell of the washing-machine. This is provided with metal heads 3, that are preferably of cast-iron and contain the central journals 4 for the trunnions 5 of the washer-cylinder 6. This washer-cylinder is perforated. The trunnion 5 at one end thereof is extended to receive the driving-gear 6 which is fixed upon said trunnion. The shell 2 is mounted upon suitable legs 7. Both the cylinder and the shell are provided with doors through which the cylinder may be filled and emptied. Suitable means are provided for filling the

shell with water and for heating and emptying the same. On the metal head 3 is a bracket 8 for the driving and reversing mechanism. The main bearings 9 and 10 of the bracket or outrigger 8 carry a driving-shaft 11, upon which the driving or belt pulley 12 is mounted.

13 is the driving-pinion, which meshes with the large gear 6 and by means of which the cylinder is driven first in one direction and then in the opposite direction.

The driving-pulley 12 has attached to it the pinion 14, the hub 14' of which is secured within the hub 12' of the pulley 12. Again, within the pinion 14, between same and the shaft 11, is a small pinion 16, the long hub or sleeve 16' of which forms the actual journal of the parts 12 and 14 upon the shaft 11, said parts all being adapted for free rotation upon the shaft except as controlled by the herein-after-described clutch.

9' is a bushing or sleeve that is fixed in the bearing-box and which forms the bearing or journal for the shaft 11 and also incases the small pinion 16. A similar bushing or sleeve 10' is provided in the box or bearing 10 at the opposite end of the shaft, and the shaft 11 is held thereby against longitudinal movement in its bearings.

17 is a pinion corresponding to the pinion 14, but preferably larger than the same, and has a long hub 17', that is joined to or is integral with the pinion 13, said pinions 13 and 17 being revolvable upon the shaft 11 except as controlled by the herein-after-described clutch. The pinions 14 and 17 are provided with annular recesses 14" and 17", respectively, in their adjacent sides, and this annular space surrounding the shaft 11 is filled by the collar 18, that is secured to the shaft 11 by a key or keys 18', as best shown in Fig. 8. The collar 18, as shown in Figs. 4, 8, 9, 10, and 11, is provided on opposite sides or ends with overhanging lugs 19, between which and the shaft 11 considerable spaces are provided. These spaces are occupied by the curved, tapered, or wedge-shaped clutch-pawls 20 20 21 21, a pair thereof being provided on each side of the collar 18 between the collar 18 and the pinions 14 and 17, respectively. The clutch-pawls 20 21 are provided at their small ends with the pin or pivot portions 22, which are parallel with the shaft 11 and are held in sockets provided therefor in the pinions 14 and 17. Thus the clutch-pawls 20 are pivotally attached to the pinion 14 to rotate therewith, while the clutch-pawls 21 are pivotally attached to the pinion 17 for rotation therewith, and, as before stated, the collar 18, with its lugs 19, is attached to the shaft 11.

The shaft 11 is a tube and contains the smaller shaft or rod 23, which is freely slideable therein, being provided with reduced portions 23' in order to reduce the friction

between the parts 11 and 23. That portion of the shaft 11 which is inclosed by the collar 18 and the pawls 20 21 is provided with the slot 24, and the rod 23 has a cross-key 25 fastened in it and which extends out through the slots 24 in the shaft 11. The key 25 is of less width than the collar 18, measured across the lugs 19 thereof, and the outer ends of the key 25 are provided with the opposite bevels 26, whereby the key 25 is made a double wedge. The inner surfaces 20' and 21' of respective pawls 20 and 21 are beveled to correspond with the pitch of the wedge-key 25, and when the rod 23 is moved in the shaft 10 in one direction or the other it will engage with the corresponding pair of wedge or clutch pawls 20 or 21 and catch the same between the key 25 and the collar 18, and thereby clutch the corresponding pinions 14 or 17 upon said shaft 11. The pawls 20 and 21, as will be noted, extend in opposite directions around the shaft 11, with the result that they are adapted for driving the shaft in opposite directions as required for the reverse rotations of the washing-cylinder.

As before explained, the pinion 14 is fixed to the belt-pulley 12, which latter is driven constantly in one direction. The pinion 17 is coupled to the belt-pulley 12 by means of the back gears. (Shown in Figs. 4 and 5.) The construction in detail comprises the short post or arm 27, projecting from the bracket or outrigger 8 and provided with two stud-shafts 28 and 29, which are parallel with the shaft 11, extending inward toward the closed side of the belt-pulley. The shaft 28 is nearer the center of the shaft 11 than is the stud-shaft 29, and upon the shaft 28 is a pinion 30, that meshes with the pinion 14 and also meshes with a smaller pinion 31, provided upon the adjacent shaft 29. The shaft 29 also carries a pinion 32, that is larger than the pinion 31 and which rotates therewith and meshes with the pinion 17. By means of these idlers the pinions 14 and 17 are caused to rotate at the same speed, but in opposite directions, whereby the shaft 11, through the medium of the clutch mechanism described, may be rotated in either direction from the belt or power pulley 12.

The mechanism thus far described presents a neat appearance, as all of the small gears or pinions and the clutch mechanism are concealed within the belt-pulley 12, the outer side or end of which is preferably closed by a solid web, as shown, said web being offset from the face of the pulley to accommodate the several pinions within the pulley.

The shifting-rod 23, which controls the clutch, extends out through the end of the shaft 11 beyond the bearing 9, and it is obvious that while the pulley 12 is in rotation the shaft 11, and therethrough the washer-cylinder, may be caused to rotate in either direction. It is further obvious that the

washer-cylinder is made to alternate in direction of rotation by intermittently operating the shifter-rod 23, and in order to secure the best results it is necessary that the rotations of the washer-cylinder shall be identical as to the number of revolutions in each direction. The reversal of the shaft 11 and the washer-cylinder by the throw of the rod 23 may be secured by means of a device operating with the shaft 11 or, in other words, operated by the rotation of the washer-cylinder; but such a device would be objectionable by reason of the fact that the shifting of the clutch would be dependent upon the momentum of the washer-cylinder, which varies with the position that the articles in the cylinder may assume at the moment of shifting or reversal. With such a contrivance it might happen that the shifting of the clutch at one moment of reversal would require more time than at another, and the result would be that the cylinder would rotate at least a part of a revolution farther in one direction than in the other. The frequent repetition of this would cause the objectionable wadding or balling of the articles in the cylinder, which it is the purpose of this invention to avoid. Hence in shifting the rod 23, by which the number of rotations of the cylinder is controlled, I employ a mechanism that is positively driven from the belt-pulley 12 and which will operate with absolute accuracy as to time and distance of rotation, being rendered wholly independent of the varying conditions in the washer-cylinder.

The washers that are now in use are each adjusted for a given number of cylinder revolutions. Some laundrymen prefer that the cylinder shall rotate twice before reversal, others arrange to rotate the cylinder three times in each direction, and still others use washers that make four revolutions after each reversal. In order to adapt my washer to the varying demands of the trade, I not only provide the positive reversing mechanism referred to, but adapt the same for easy adjustment, so that the cylinder may be operated at one, two, three, or four revolutions, as the purchaser may wish. This adjusting mechanism forms a part of the reversing mechanism and will be described in connection therewith.

The small pinion 16, above referred to, is secured to the belt-pulley 12, and this is employed for driving the reversing mechanism. As shown in Figs. 4, 6, and 7, the pinion 16 meshes with and drives the larger gear 33, which is journaled upon a stud 34, provided in the back of the bracket 8. On the same stud is a pinion 35, that rotates with the gear 33 and meshes with a large gear 36, that is fixed upon a shaft 37, having bearings in the bracket 8, and is parallel with the stud 34. The stud 34 extends through the bracket 8, having a large end or portion 34', as shown

in Figs. 4 and 7. The bracket 8 is expanded in that portion beneath the bearing 9 to accommodate the two pyramids of gears 38 and 39. In the outer side of the bracket 8 is a large opening 40, that is concentric with the stud 34 and is filled by the large cam-wheel 41, mounted on the sleeve 42, and rotates in the opening or bearing 40. The gears 38 and the cam-wheel 41 are secured to the sleeve 42 by a key 43, and the cam-wheel 41 is driven by one or the other of said gears. This is accomplished by means of the gears 39, which are of different dimensions and which are journaled upon the shaft 37, that is driven positively, said gears 39 being in mesh with the corresponding gears 38.

The inner side of the bearing-bracket 8 is provided with an annular opening 44, that is concentric with the shaft 37, and this opening is closed by the filler or washer 45, secured therein, and which with the outer side of the bracket 8 provides the bearings for the shaft 37. The shaft 37 has a groove 46 to accommodate a sliding key 47, held outward by a light spring 48 and movable back and forth in the groove 46 by the lever 47', which is easily moved. The gears 39 are provided with keyways 49, in which the key 47 engages. To prevent the bridging of the key across two gears at once, the gears 39 are separated by the collars or rings 50, whereby the key is forced inwardly as it is moved from one gear 39 to the other. It is obvious that the speed of the cam-wheel 41 depends upon the position of the sliding key 47. The outer end of the cam-wheel 41 is recessed for the washer 34", that is fastened to the end of the stationary stud 34. Said cam-wheel 41 is provided with a cam-groove 41' for moving the wedge or clutch rod 23.

As shown best in Fig. 2, the bracket 8 is provided with an extension 8' upon that part of the bracket which contains the gears 39. On this extension I provide the shifting lever 51, having a pin or stud 52, that extends into the cam-groove 41' of the cam-wheel 41. At the upper end of the lever 51 is a yoke 51', that is pinned or pivoted to a block 53 on the projecting end of the rod 23, whereby as the cam-wheel is rotated said rod 23 will be moved first in one direction and then in the opposite to reverse the rotation of the shaft 11 and the washer-cylinder, driven therefrom.

Referring to the clutch and the clutch-pawls 20-21, it will be noted that these parts are in constant rotation and that one set or the other of the pawls is always in rotation in a direction opposite to that of the shaft 11 and the collar 18 thereon. This being the case, it will sometimes happen that the pawls will not be caught instantly upon the shifting of the wedge or may be struck upon their large ends, in which case the rod 23 would be prevented from moving. As this may occur

at the instant of the action of the cam-wheel 41, I provide means to prevent breakage of parts or the locking of the parts, which means comprises a cushion on each side of 5 the block 53. These cushions comprise the collars 54 on the rod 23 and the spring cases or collars 55, separated by the springs 56. The collars 54 55 are allowed a certain freedom of movement that is substantially equal 10 to the width of the pawls 20 21, and by this means the shifting lever and the block 53 are permitted to move, if necessary, prior to the full movement of the rod 23, which movement will be completed as soon as the 15 pawls 20 or 21, that are attacked by the wedge, move into the proper position.

In ordinary practice the speed of the shaft 11 is six to one with relation to the washer-cylinder, and by means of the positively-driven cam-wheel and the nests of gears 38 20 39 for driving the same the washer-cylinder may be reversed after every revolution or 25 every second, third, or fourth revolution, as the user may desire, the train of reversing-gears being proportioned to the speeds of the shaft 11 and cylinder.

The operation of my washing-machine is as follows: The door of the cylinder is brought opposite the door in the shell, which has been 30 previously filled. The cylinder is then filled with garments to be washed, whereupon the doors are closed, and the cylinder is ready for rotation. Previous to starting the machine the operator decides as to the number of rotations which the shell shall make in each direction before reversal. If he decides to reverse the cylinder at each revolution, he will 35 by means of the lever 47" place the small key 47 so that it will engage with the largest gear 40 of the nest of gears 39. If he determines to reverse at the end of every second revolution, the key 47 will be placed as shown in Fig. 7. If four revolutions are desired before reversal, the key is pushed in to engage 45 with the smallest of the gears 39. The driving-pulley 12 is then rotated by means of the belt. At this moment it is assumed that the shaft 23 is in its middle position, with neither wedge 25 in engagement with the clutch. 50 The operator then places the pin 52 of the shifting-lever 51 in the groove 41' of the cam-wheel 41, and this cam-wheel being driven from the pulley 12 imparts the throw to the rod or shaft 23 to clutch either the 55 gear 14 or the gear 17 to the shaft 11. It should be understood that the cam 41 is rotated constantly in one direction, being in this respect like to the driving-pulley 12. The washing-machine cylinder is driven in one 60 direction or the other, as before explained, according to the gear-pinion 14 17 that is momentarily fastened to the driving-shaft 11, and the duration of the rotation of the cylinder in either direction is determined by 65 the ratio of speed between the driving-pulley

12 and the cam-wheel 41. When once the sliding key 47' has been adjusted, this ratio is fixed, because the cam-wheel 41 is then positively geared to the driving-pulley 12. The positive gear connection is traced through the pinion 16 and gears 33, 35, 36, 39, and 38. The engagement of the cam-surface of the pulley 41 (see dotted lines, Fig. 7) with the shifting-pin 52 of the lever 51 in either of its positions causes the quick longitudinal throw of the shaft or rod 23 that is necessary to instantly transfer the wedges 25 from the pair of tapered clutch-pawl in one pinion 14 17 to the pair of pawls in the other. The movement of the shaft 23 is so quick that the reversal of the shaft 11 is accomplished almost instantly and with absolute regularity during a succession of reversals, with the result that the lengths of the rotary movements of the washing-cylinder are identical 85 in the two directions.

My driving mechanism, which possesses the principal and important quality of positiveness in operation, has the added advantages of simplicity, durability, adjustability, 90 noiselessness, neatness, and compactness.

It is obvious that connected and alternated driving means may be provided in forms other than that herein illustrated, and, further, that the gist of this invention resides, 95 primarily, in the combination, with the cylinder-driving shaft and a driving member or members, of means that are positively driven from the driving member without direct reference to said shaft and which means are relied upon for the operation of reversing the rotation of the driving-shaft according to the distance of the rotary travel of said driving member instead of according to the duration of its rotation, as in the old-style mechanisms.

For the above and other reasons I do not limit my invention to the specific construction and combinations of parts herein shown and described.

Having thus described my invention, I claim as new and desire to secure by Letters Patent—

1. The driving and reversing mechanism comprising the shaft, the bracket wherein the same is journaled, means for driving the shaft in opposite directions, a shifting-cam arranged upon said bracket and the reversing and regulating mechanism concealed within said bracket, for operating said cam, substantially as described.

2. The driving and reversing mechanism comprising the shaft in combination with the drivers mounted thereon, the driver-clutches, the rod therefor longitudinally movable in said shaft, a positively-actuated shifter and cushions interposed between said rod and shifter, substantially as described.

3. The driving and reversing mechanism comprising the shaft, in combination with,

the driving-pulley mounted thereon, the driver-pinion connected with said pulley for driving the shaft in one direction, the rotatively-opposed pinion journaled on said shaft 5 and connected with said driver-pinion within said pulley, for driving the shaft in the opposite direction, the clutch mechanism arranged between said pinions, the clutch-rod revolvable with said shaft and means for operating 10 said rod, substantially as described.

4. In a driving and reversing mechanism, the combination of a reversible member, with driving and reversing mechanism therefor, and means for regulably controlling and determining the number of rotations of said 15 reversible member in each direction, substantially as described.

5. In a driving and reversing mechanism, the combination of a shaft with reversible driving means on said shaft, clutches for engaging said means with the shaft, and a clutch-operating cam positively driven in one direction only by said means, substantially as described.

25 6. In a driving and reversing mechanism, a member for alternative rotation, in combination with a driving-shaft therefor, drivers mounted thereon, means for continuously rotating the drivers in opposite directions, reciprocating means for connecting either of 30 the drivers with said shaft, a rotary cam for actuating the reciprocating means, and mechanism whereby the operation of the cam may be variously timed, for controlling the peripheral travel of said member, substantially as described.

7. In a driving and reversing mechanism, a rotary working member, in combination with a driving-shaft therefor, drivers mounted on said shaft for rotating the same in opposite directions, a shifter controlling the operation of the shaft by said drivers, a shifter-actuating cam continuously driven in one direction, with one of said drivers, and means for varying the relative speeds of said cam and driver, substantially as described.

8. In a driving and reversing mechanism, the combination of a member for alternative rotation, with clutches for the periodical reversal of said member, and having a movable part, a clutch-shifting cam, and variable-speed gears for driving said cam, for increasing or decreasing the periods of rotation of said member, substantially as described.

55 9. In a driving and reversing mechanism, the combination of a member for alternative rotation, with clutches for the periodical reversal of said member, oppositely-rotating drivers, a clutch-shifting cam and a variable-speed gear interposed between one of said drivers and said cam, substantially as described.

10. In a driving and reversing mechanism, the combination of a member for alternative 65 rotation, and a reversing-shaft therefor, with

stem movable longitudinally within said shaft, drivers mounted concentrically with the reversing-shaft, clutches operated by said stem, for connecting either of the drivers with said shaft, and means actuated by one of the drivers for imparting longitudinal reciprocation to said stem, substantially as described.

11. In a driving and reversing mechanism, the combination of a member for alternative 75 rotation, with a longitudinally-moving stem operating a reversing mechanism for said member, a cam-wheel actuating said stem longitudinally in either direction, and a plurality of pinions of different diameters for 80 operating said cam-wheel at varying speed, substantially as described.

12. In a driving and reversing mechanism, the combination of a member for alternative rotation, with oppositely-moving drivers for 85 actuating said member in either direction, clutches for connecting said member alternately with the drivers, a longitudinally-moving stem operating said clutches, two sets of intermeshing gears actuated from one 90 of said drivers, a cam-wheel operated by said gears, for imparting a longitudinal movement to said stem, a hollow shaft for one set of gears, and a manually-operated pin within the hollow shaft whereby said shaft may be 95 operatively connected to any one of the gears mounted thereon, substantially as described.

13. In a driving and reversing mechanism, the combination of a member for alternative rotation, with a hollow reversing-shaft for 100 said member, two drivers operated constantly in opposite directions, and mounted concentrically with the reversing-shaft, a stem mounted within the reversing-shaft, and operable longitudinally for connecting 105 either of the drivers with said shaft, a plurality of intermeshing pinions actuated by one of said drivers, a cam-wheel operated by said pinions and reciprocating said stem longitudinally in either direction, and manually-actuated means for operatively connecting 110 said pinions with one of the drivers, substantially as described.

14. In a driving and reversing mechanism, the combination of a member for alternative 115 rotation, a reversing-shaft for said member, drivers revolving in opposite directions, clutches for the drivers, a longitudinally-moving clutch-actuating stem or shifter, and means for cushioning the stroke of said shifter 120 in both directions, substantially as described.

15. In a driving and reversing mechanism, the combination of a working member, with means including two drivers for alternatively rotating said member, two pyramids of 125 gears operatively connected with one of said drivers, a cam-wheel secured on the stem of one pyramid of gears, a hollow shaft for the other gears, constantly operated in one direction by one of said drivers, and a man- 130

ually-operated pin for engaging the hollow shaft with any one of its gears, substantially as described.

16. In a driving and reversing mechanism, 5 the combination of a member for alternative rotation, with a reversing-shaft for said member, drivers for said shaft revolving in opposite directions, clutches for connecting said drivers to the shaft, a longitudinally-moving stem for operating said clutches, a pair of springs for cushioning said stem at either end of its stroke, a cam-wheel operating said stem, two series of pinions actuating said cam-wheel, and a manually-operated key 15 within the shaft of one of the series of pinions, for transmitting the motion of one of the drivers to the longitudinally-moving stem, substantially as described.

17. In a driving and reversing mechanism, 20 a member for alternative rotation, in combination with a shaft continuously rotated in one direction, a reversing-shaft rotated alternatively, drivers for the reversing-shaft, clutches actuated by a longitudinally-sliding 25 stem for engaging the drivers with the reversing-shaft alternately, a pyramid of gears loosely mounted on a hollow shaft, a second pyramid of gears intermeshing with the first and rigidly mounted on a stem, a cam-wheel 30 also rigidly secured to the stem, gear-wheels connecting one of the drivers to the said hollow shaft, a pivotally-mounted lever secured to said sliding stem, means for manually connecting the hollow shaft with any one of its 35 gears, whereby the speed of the cam-wheel may be varied, and means for manually connecting said lever to the cam-wheel, whereby the sliding stem is actuated longitudinally, substantially as described.

40 18. In a driving and reversing mechanism, a main pulley constantly rotated in one direction, in combination with a reversing-shaft operated by said pulley and rotated in the same direction, a member for alternative rotation, drivers for actuating said member in either direction, clutches for connecting either of the drivers with the reversing-shaft, a stem within said shaft, for operating the 45 clutches, a cam-wheel for moving said stem longitudinally, in either direction, operative connection between one of the drivers and said cam-wheel, springs for cushioning the stroke of the stem, a device for varying the speed of the cam-wheel, means for operatively connecting said device with the cam-wheel, and means for operatively connecting the cam-wheel and the stem, substantially as 55 described.

19. In a driving and reversing mechanism, 60 a working member for alternative rotation, in combination with a driving-shaft coupled thereto, a driving-pulley mounted upon the shaft, oppositely-rotating drivers also mounted on the shaft, means for connecting either 65 of said drivers with said shaft, and means

geared to said pulley and driven thereby, controlling the connection between said pulley, drivers and shaft, substantially as described.

20. In a driving and reversing mechanism, 70 a working member for alternative rotation, in combination with a driving-shaft coupled thereto, a pulley mounted on the shaft, an oppositely-rotated driver mounted on the shaft, a shifter for causing the shaft to be 75 driven by the pulley or the driver, and a shifter-cam variably geared to said pulley, substantially as described.

21. In a driving and reversing mechanism, 80 the combination of a working member with a stationary body whereon the same is arranged, a bracket extending from said body, a power-transmitting shaft arranged in said bracket and geared to said member, reversely-operated drivers on said shaft, means continuously actuating the same, a clutch for connecting either of the drivers to the shaft, a clutch-shifter, and a clutch-actuated device arranged on said bracket and geared to one of said drivers, substantially as described. 90

22. In a driving and reversing mechanism, 95 the combination of a working member with a stationary body whereon the same is arranged, a bracket extending from said body, a power-transmitting shaft arranged in said bracket and geared to said member, reversely-operated drivers on said shaft, means continuously actuating the same, a clutch for connecting either of the drivers to the shaft, a clutch-shifter, and means upon said bracket 100 for altering the relative speeds of the shifter-actuating device and the driver to which it is geared, whereby the operation of the clutch may be timed and the travel of the working member altered, substantially as described. 105

23. In a driving and reversing mechanism, a body, a member mounted thereon for alternative rotation, and a driving-shaft coupled to said member, in combination with the bracket having bearings for said shaft, and driving, reversing and variable-gear mechanisms associated with said shaft on said bracket, substantially as described. 110

24. In a driving and reversing mechanism, 115 a working member for alternative rotation, in combination with a driving-shaft coupled to said member, oppositely-driven clutches adapted to rotate said shaft in opposite directions, a clutch-shifter and a shifter-cam rotated continuously in one direction, substantially as described. 120

25. In a driving and reversing mechanism, 125 a working member for alternative rotation, in combination with a driving-shaft coupled to said member, oppositely-driven clutches adapted to drive said shaft in opposite directions, a clutch-shifter, and a normally constant-speed single-direction shifter-cam adapted to operate said shifter periodically, substantially as described. 130

26. In a driving and reversing mechanism, a working member for alternative rotation, in combination with a driving-shaft coupled to said member, means for rotating said shaft in opposite directions, a shifter controlling the action of said means, a normally constant-speed single-direction shifter-cam adapted to operate said shifter periodically and means for changing the speed of said cam, to hasten or retard the action of said shifter, substantially as described. 40
27. In a driving and reversing mechanism, a working member, in combination with a driving-shaft coupled to said member, constantly and oppositely driven clutches, a shifter for engaging either thereof with said shaft, and a variable-speed shifter-cam mechanism continuously driven from and with one of said clutches, substantially as 45 described, and for the purpose described. 50
28. In a driving and reversing mechanism, a working member for alternative rotation, in combination with an alternating mechanism coupled to said member and means for relatively hastening or retarding the reversals thereof to vary the number of revolutions of said member in each direction, substantially as described. 55
29. In a driving and reversing mechanism, a working member for alternative rotation, in combination with an alternating mechanism coupled to said member and means for relatively hastening or retarding the reversals thereof to vary the number of revolutions of said member in each direction, said 60 means being positively actuated by a member of said alternating mechanism, substantially as described. 65
30. In a driving and reversing mechanism, a working member for alternative rotation, in combination with an alternating mechanism coupled thereto and including oppositely-driven parts and a shifter, a constantly-driven single-direction cam for actuating said shifter periodically and means for varying the speed of said cam, substantially as 70 described. 75
31. In a driving and reversing mechanism, a working member for alternative rotation, in combination with a driving-shaft, coupled to said member, a single-direction power-pulley, shaft-driving clutches, adapted to be rotated in opposite directions by said pulley, a clutch-shifter and a shifter-cam continuously rotated by said pulley, to periodically 80 reverse said clutches and, therethrough, said shaft and member, substantially as described. 85
32. In a driving and reversing mechanism, a working member for alternative rotation, in combination with a driving-shaft geared thereto, a power-pulley mounted on said shaft, opposite-direction clutches located within said pulley and driven in opposite directions thereby, a clutch-shifter, internal to said shaft, a shifter-cam external to said shaft and means interposed between said cam and shaft for driving and varying the operating time of said cam, substantially as 90 described. 95

In testimony whereof I have hereunto set my hand, in the presence of two subscribing witnesses, this 2d day of September, 1902.

FREDERICK SNOW.
